US0D1074276S

(12) **United States Design Patent** (10) Patent No.: **US D1,074,276 S**
(45) Date of Patent: ** May 13, 2025

(54) **SHELVING**

(71) Applicant: **PBO International Trade LLC**,
Albuquerque, NM (US)

(72) Inventor: **Pablo Borrajo**, Albuquerque, NM (US)

(**) Term: **15 Years**

(21) Appl. No.: **35/520,486**

(22) Filed: **Mar. 8, 2024**

(80) **Hague Agreement Data**

Int. Filing Date: **Mar. 8, 2024**

Int. Reg. No.: **DM/236092**

Int. Reg. Date: **Mar. 8, 2024**

Int. Reg. Pub. Date: **Apr. 5, 2024**

(51) LOC (15) Cl. 06-06

(52) U.S. Cl.

USPC **D6/678.1**

(58) **Field of Classification Search**

USPC D6/672, 675, 675.1, 675.3, 676.3, 705
CPC A47B 43/00; A47B 96/00; A47B 96/02;

A47B 5/0081; A47F 5/0043; A47F 5/10
